PROCESS OF FORMING THREAD

Carl F. Gram, Rowayton, Conn., assignor to North American Rayon Corporation, New York, N. Y., a corporation of Delaware

Application August 3, 1945, Serial No. 608,655

1. Claim. (Cl. 18—54)

1 In the production of high tenacity rayon yarn such as is employed in the production of heavy duty tires used on aircraft, trucks, gun carriages and the like where severe service conditions are encountered, many important factors enter into the method of treating the yarn. One of these factors is the rapidity with which impurities contained in such yarn, as a result of its formation, can be removed from the individual filaments of which the yarn is composed:

High tenacity viscose yarn, for example, is ordinarily produced by extruding a viscose spinning solution into an acid spin bath under conditions to form a thread, withdrawing the thread thus formed from the bath before complete regeneration of the cellulose content of the viscose has been completed, passing the incompletely regenerated thread through a hot water bath under stretching to accelerate regeneration, and then collecting it on a perforated bobbin upon which complete regeneration of the cellulose takes place and upon which it is subsequently subjected to after-treatment such as washing to remove acid and desulphurizing to remove sulphur therefrom. Further after-treatment may include additional washing, bleaching, sizing and like steps commonly practiced in the rayon and allied textile arts.

One feature of great importance in the preservation of the tensile strength of such yarn is the prompt and complete removal of the acid as soon as regeneration of the cellulose has attained substantial completion so as to avoid acid attack on the cellulose and consequent degeneration thereof.

In after-treating packages of such synthetic thread much difficulty has been experienced in securing adequate penetration of the after-treating liquids into the layers of yarn so that it sometimes occurs that complete treatment of the packages required such a long period of time that acid degradation of the yarn was experienced. While such a condition can in some small measure be tolerated in yarn of ordinary commercial quality having less than 100 filaments, the complete removal of impurities from each portion of each filament as rapidly as possible becomes of paramount importance where the utmost strength of every filament is depended upon, as in the production of fabric for heavy duty tires, etc.

In the ordinary production of synthetic yarn by the stretch spinning method the bundle of filaments forming the yarn assume a parallel arrangement and lie substantially in one plane thus forming a flat ribbon like yarn strand. Prior art teaches (see British Patent No. 297,063) that

2 liquid penetration of a yarn package is better effected when the filaments composing the yarn are twisted. I have discovered that it is not the twisting but the arrangement of the filaments in the form of a circular cylindrical bundle, rather than in a flat ribbon like strand, that effects better penetration of after-treating liquid into the yarn package. United States Patents Nos. 1,492,316 and 2,036,174 both disclose means for at least partially twisting a yarn either during or preparatory to liquid treatment. So far as I am aware however there is no prior art which combines shaping a yarn strand with the stretching of the filaments of which the strand is composed and immediately packaging the yarn for after-treatment.

The primary object of this invention is to reduce to a minimum the time required adequately to remove the impurities from freshly spun synthetic yarn having at least 100 filaments.

Another object is to facilitate the washing out of the acid as soon as regeneration of the cellulose content of the yarn is completed.

A further object is to so orient the filaments of a yarn strand immediately before its collection that each portion of the strand retains a substantially circular cylindrical cross-section so that when the strand is cross-wound on a perforated bobbin in a plurality of layers it forms a package which is readily pervious to after-treating fluids.

The above and other objects may be attained by employing this invention which embodies among its features a guide roller having a plurality of spaced flanges, the said guide roller being at an angle to and operating in conjunction with a godet wheel around both of which the yarn on its way from its source of origin to its point of collection is given a number of helical turns in such a manner that it rides the flanges and is thereby given a slight rolling movement whereby the filaments are caused to so orient themselves that the yarn assumes a substantially circular cross-section.

Another feature embodies collecting the yarn in package form while it still retains the circular cross-section imparted to it by the flanged roller and godet wheel combination so that during the after-treatment of the package rapid removal of the impurities can be achieved.

50. In the drawings:

Fig. 1 is a perspective view of a portion of a spinning machine equipped with a grooved guide roller for condensing a plurality of filaments into a strand which is substantially circular in cross-section,

Fig. 2 is a front view of a godet wheel and a guide roller assembly as employed in connection with this invention.

Fig. 3 is a side view of Fig. 2, and

Fig. 4 is a fragmentary sectional view through a thread package embodying this invention.

Referring to the drawings in detail a spinning machine designated generally 10 includes a spinning trough 11 containing a coagulant into which a spinning solution is introduced through a spinning pump with candle filter 12 and goose neck 13 which terminates beneath the surface of the coagulant in a spinnerette (not shown). Mounted above the spinnerette on a substantially horizontal axis is a godet wheel and guide roller 14 and 15 respectively about which the thread 16, formed by contact of the spinning solution with the coagulant, is wound for a few turns in the form of a helix. Mounted adjacent and coextending parallel with the trough 11 is a trough 17 containing a hot aqueous liquid having a temperature above 60° C., preferably hot water, beneath the surface of which is disposed a guide roller (not shown) about which the thread upon leaving the godet and guide roller 14 and 15 is guided.

From the guide roller, which is immersed in the hot, aqueous liquid, the thread passes upwardly to a second godet wheel 18 which operates about a horizontal axis at a somewhat higher peripheral speed than the godet wheel 14 so as to impart stretch to thread as it passes through said hot liquid. Mounted adjacent the godet wheel 18 on an axis of about 14° to the horizontal is a guide roller 19 having formed in its periphery a plurality of spaced grooves 20 in which the thread is laid in the form of a helix. As shown in Fig. 3 the thread entering the grooves rides the flanges as it traverses the godet wheel 18 and guide roller 20, and the filaments forming the thread are thus condensed and manipulated so as to form a strand which is substantially circular in cross-section.

Leaving the godet wheel 18 and guide roller 19, the thread thus formed into a strand of circular cross-section passes downwardly beneath a grooved guide roller 21 and thence upwardly through a traverse mechanism 22 to a collecting bobbin 23 upon which the strand is cross-wound in a package 24 ready for further treatment.

Due to the circular cross-section of the thread strand the thread layers in the package 24 form interstices 25 (Fig. 4) through which treating fluids readily can pass, and hence the acid and impurities contained in the thread can be removed before any deleterious effects are experienced.

Actual tests have shown that thread packages produced under ordinary conditions in which the thread strand assumed a flat ribbon like form, possessed a perviousness which would allow them to pass only about six and one-half liters of liquid per hour whereas like bobbins wound under like conditions except that the thread strand was so shaped as to be circular in cross-section possessed a perviousness which enabled them to pass over forty liters of liquid per hour. Tests made on bobbins wound with 1100 denier high strength yarn containing 480 filaments in accordance with this invention, show substantially complete acid removal with standard pressure vacuum washing equipment in a period of fifteen minutes whereas

like tests made on bobbins wound with like yarn in accordance with the conventional practice and washed as recited above, show at the end of a sixty minute washing period an acid content of over fifty percent of that initially contained in the package. As a consequence, by employing this invention the high strength imparted to the yarn due to the stretching and hot water treatments can be preserved and the acid and impurities can be flushed out of the yarn package as soon as regeneration is completed.

While in the foregoing there has been shown and described the preferred embodiment of this invention, it is to be understood that minor changes in the details of construction, combination and arrangement of parts may be resorted to without departing from the spirit and scope of the invention as claimed. The term "high-tenacity rayon yarn" denotes yarn spun from viscose, cuprammonium cellulose, viscose-casein solutions, etc. having at least 2 grams dry strength per denier.

I claim:

In the method of producing high tenacity rayon yarn wherein a spinning solution is extruded into a spin bath under conditions to form a multifilament yarn strand, the resultant strand being then directed through a hot aqueous liquid, subjected to stretch, and finally collected on a perforated bobbin in the form of a cross-wound take-up package ready for after-treatment, the improvement comprising the steps of forming said multifilament strand in a spin bath of relatively low temperature, withdrawing the strand as fast as formed from the bath by means of a first godet and roller unit before complete regeneration has set in, then passing said strand through an aqueous bath of substantially higher temperature to accelerate regeneration thereof, withdrawing it therefrom by means of a second godet and roller unit driven at a slightly higher peripheral speed than said first unit to impart stretch to said strand, and, while stretching said strand and while the regeneration thereof is continuing in accelerated fashion, abruptly changing the path of said strand a plurality of times for a short distance of travel and in such angular directions during its passage over said second godet as to impart a rolling motion thereto and cause it to acquire a lasting, substantially circular cylindrical shape and collecting said circular strand into a cross-wound package having a multitude of interstices.
